FRANK H. SCHWERIN, OF BELLEVUE, PENNSYLVANIA, ASSIGNOR TO THE DUFF-NORTON MANUFACTURING COMPANY, OF PITTSBURGH, PENNSYLVANIA, A CORPORATION OF PENNSYLVANIA

SCREW JACK

Application filed December 5, 1929. Serial No. 411,770.

The invention relates to self-lowering screw jacks of the centrifugal governor controlled type. The particular object of the invention has been to provide a jack suitable for use in jacking up and lowering freight cars. 5

One of the principal features which has been sought is lightness in weight, so that the jack can be readily carried about. Another object is to secure a construction which is 10 adapted for economical manufacture. The purpose, also, is to provide a jack possessing these advantages, which shall be safe and strong, in which accurate centering and alignment of the working parts is readily obtained, and which is easy to repair. 15

In the accompanying drawings, forming part hereof:

Fig. 1 is a vertical longitudinal section 20 through a jack embodying the invention;

Fig. 2 is a section taken on the line 2—2 of Fig. 1;

Fig. 3 is a section taken on the line 3—3 of Fig. 2; and

Fig. 4 is a section taken on the line 4—4 25 of Fig. 3.

The jack has a base 2 from which rises a hollow cylindrical standard 3. These parts, instead of being made in a single heavy and 30 expensive casting as heretofore, consist of two pieces. The base is a casting formed with an upstanding collar 4, which is braced to the outwardly projecting portion of the base by ribs 5. The standard consists of a

35 section of commercial tube which is stepped into the collar 4 and rests at its lower end on the portion of the base inside the collar. A transverse pin 6 passing through the collar and the lower end of the standard connects 40 these parts firmly together. This construction of the base and standard affords a high degree of strength while greatly reducing the weight and minimizing the amount of machine work required. This portion of the 45 jack is far lighter and much less costly than the usual plan of a base and standard in one piece.

A nut 7 is fixed in the upper end of the standard and is engaged by a steep-pitch or 50 run-down screw 8. A bevel gear 9 is secured

to the upper end of an extension 10 of the screw, and a thrust bearing 11 is interposed between this gear and the integral head 12 of a shell 13 which slides on the outside of the standard. From the lower end of this 55 shell there projects a toe-lift bracket 14.

The shell 13 is made with an opening 15 in one side immediately below the head, the lower edge of this opening being remote from the lower end of the shell. A bonnet 60 16 is applied over this opening, and is secured to the side face of the shell by screws 17 passing through basal flanges 18 on the bonnet.

In the outer end of the bonnet there is a 65 bearing 19 for an operating shaft 20, this shaft projecting outside the bonnet and being formed to receive the usual ratchet wheel and socketed ratchet case, which it has not been thought necessary to illustrate since 70 they are well known.

A circular plate 21 is held in a rebate 22 in the inner end of the bonnet, between the shoulder of the rebate and the outer face of the shell, and in the center of this plate there 75 is a bearing 23 for the inner portion of the operating shaft. This bearing is reliably centered and aligned with the bearing 19 by virtue of the circular plate fitting in the circular rebate. A bevel gear 24 formed on or 80 secured to the inner end of the shaft 20 at the side of the plate 21 which faces the interior of the shell, meshes with the bevel gear 9.

At the other side of said plate, a spur gear 85 25 is mounted loosely on or around the operating shaft. This gear has ratchet teeth 26 on its outer face to engage ratchet teeth on a clutch collar 27, which like the gear is located inside the main chamber 28 of the 90 bonnet, between the bearing plate 21 and the outer bearing 19. The clutch collar 27 is slidable lengthwise of the operating shaft but held thereto in respect to rotation by feather projections on the shaft, and is pressed into 95 engagement with the ratchet teeth on the spur gear by a spring 29.

The ratchet teeth are so formed that when the shaft 20 is turned in the direction to rotate the screw 8 to raise the shell 13, the ratchet 100

teeth on the clutch collar ride idly over the cooperating teeth on the stationary gear, the clutch collar moving back and forth on the shaft under the pressure of the spring. When the lifting effort ceases, the perpendicular faces of the teeth bear against each other, so that the shell is held against dropping, the gear 25 being held against rotation in the lowering direction by means which will be described. Likewise, when the shell 13 is lowered, the shaft 20 rotates the gear to operate the centrifugal brake or governor hereinafter described.

The bonnet 16 has a downward extension 30 forming a supplementary gear chamber below the main chamber 28. This extension is in one piece with the bonnet and provides integral spaced walls 31 and 32, in internal bosses of which the ends of a fixed shaft 33 are supported, this shaft being parallel with the rotary operating shaft 20.

Rotatable on this shaft 33 are a spur pinion 34 and a worm wheel 35, which are suitably united together. The pinion 34 meshes with the gear 25, and the worm wheel meshes with a worm 36, the pitch of this worm gearing being such that the worm wheel can drive the worm.

The worm is formed on a shaft 37 which extends horizontally in the lowest portion of the supplementary chamber in a plane at right angles to the plane of the shafts 20 and 33. One end of the shaft 37 is journaled in a bearing 38 in an integral end wall 39 of the downward extension 30 of the bonnet, and a thrust bearing 40 is interposed at this end of the shaft.

The other end of said extension is enlarged to form a chamber 41, this chamber having a mouth which is provided with an internal, cylindrical, machined surface 42. The mouth is closed by a cap 43 having an inwardly projecting cylindrical flange 44 machined on the outside to fit the machined surface 42 of the bonnet, and machined on the inside to cooperate with the governor, as will presently appear. The cap is held in place by screws 45 and has a central boss 46 which affords a bearing for the other end of the worm shaft 37, this bearing being accurately alined with the bearing 38 by reason of the circular flange of the cap fitting in the circular opening.

The portion of the shaft 37 within the enlarged chamber 41 is formed polygonally to receive a governor disc 47. Carried by this disc and slidably on its outer face are two centrifugal segments 48. The outer face of the disc 47 has a diametrical groove 49 and the segments 48 have central ribs 50 which are guided in the grooves so that the segments move in right lines only. The segments are retained against the face of the disc by the heads of pins 51 which pass through central slots 52 in the segments and are fixed in the disc.

Recesses 53 are formed in the outer faces of the segments, near their ends, and studs 54 are set into the segments at the backs of these recesses, the projecting heads of the studs lying within the recesses. The opposite ends of two tension springs 55 are connected to the heads of these studs and normally draw the segments toward each other and away from the encircling wall of the flange 44. When the shell 13 and the load resting thereon are permitted to descend, the governor is rotated at considerable speed by the screw and gearing and clutch which have been described, and the segments are urged outward into braking contact with the encircling stationary surface, so as to retard the speed of lowering to a safe, uniform rate.

This form of governor is inexpensive to make and decidedly compact, in which respect it is an improvement over governors having tilting segments such as disclosed in my prior Patent 1,579,788 of April 6, 1926, for example, and I find it to be perfectly sensitive and reliable.

In the cap 43 with its circular flange 44 fitting a circular opening and serving to center accurately the fixed and rotary parts of the governor as well as the bearing for the worm and governor shaft, the present jack incorporates a feature covered by my patent aforesaid.

The enlargement 56 which provides the chamber 41 for the governor has a downward extension 57, the lower end of which is formed with a vertical, internally screw-threaded opening, which is engaged by a hollow screw 58. This screw is formed with an external thumb piece 59, which lies in a protected location beneath this extension of the bonnet.

A shaft 60 is pinned at 61 to the outer end of the screw 58, and projects for a distance beyond the inner end of the screw. The inner end of this shaft has a head 62 which retains a manually operated brake segment 63, the shaft being swiveled in this segment. By means of the thumb piece 59 the brake segment 63 can be set against the periphery of the disc 47 in accordance with my Patent 1,579,788 aforesaid, in order to keep the load from descending, or can be freed from the disc in order to allow the load to lower at a safe rate determined by the centrifugal governor brake.

It will be perceived that the construction of the present jack is such that all the mechanism, other than the non-rotary nut 7, the lifting screw 8 and the bevel gear 9 on the upper end of this screw are housed in the separate bonnet or casing unit 16, and that the construction of this bonnet and the manner in which the parts are mounted therein are such as to simplify machining, assembling and repair, to facilitate the alining and cen-

tering of the working parts and to secure great rigidity with comparative lightness.

The location of the mechanism well up at the top of the jack permits the provision of 5 the toe lift 14 at the lower end of the shell and still leaves a smooth exterior of sufficient length so that the jack can be conveniently carried on a man's shoulder.

I claim:

- 10 In a self-lowering screw jack, the combination with a shell having an opening in one side and the lifting screw having a bevel gear, of a separate bonnet applied to the side of the shell over said opening, said bonnet having an integral pocket extension adjacent the shell, which extension has inner and outer side walls, an end wall and an enlargement opposite said end wall, a cap closing said enlargement, an operating shaft extending 15 through and carried by said bonnet, the outer end of said operating shaft being formed to receive manual operating means and its inner end having a bevel gear meshing the bevel gear on the screw, a centrifugal brake in said 20 enlargement, and gearing, including an automatic clutch, between said operating shaft and said brake, said gearing being supported wholly on said operating shaft and by the two side walls and the end wall and cap 25 30 of said pocket extension of the bonnet.

FRANK H. SCHWERIN.
